GILBERT J. SCOFIELD, OF ALBANY, NEW YORK

PAPER-MAKING MACHINERY

Application filed September 7, 1927. Serial No. 217,908.

This invention relates to paper-making machinery and more particularly to paper-making machines wherein the pulp, or material from which the paper is made, is picked up by a rotating cylinder mold and transferred therefrom to a moving belt of felt or the like.

One of the objects of the invention is to provide a thoroughly practical means for maintaining the cylinder molds in condition for efficient operation. Another object is to provide an efficient device for thoroughly cleaning the cylinder molds. Another object is to provide a device of the above nature by means of which the entire surface of the cylinder mold may be cleaned quickly and conveniently without interrupting the operation of the machine. Another object is to provide a device of the above nature by means of which any portion of the cylinder mold may be quickly reached and quickly and thoroughly cleaned. Another object is to provide a device of the above nature which is simple and convenient to operate. Other objects will be in part obvious, or in part pointed out hereinafter.

The invention accordingly consists in the features of construction, combinations of elements and arrangements of parts as will be exemplified in the structure to be hereinafter described and the scope of the application of which will be indicated in the following claims.

In the accompanying drawing in which is shown one of the various possible embodiments of this invention,

Figure 1 is a side elevation;

Figure 2 is a view taken substantially as indicated by the line 2-2 in Figure 1, the middle portion of the apparatus being broken away, and

Figure 3 is a section taken as indicated by the line 3-3 in Figure 2.

Similar reference characters refer to similar parts throughout the several views of the drawing.

Referring now to the drawing in detail, there are shown the side walls 10 and 11 of a vat in which, mixed with water, is contained the pulp or similar material from which the

paper is made. In this vat is a large cylinder 12 whose surface consists of a wire mesh or screen 13. The cylinder shown herein is supported by spokes 14 projecting outwardly from a hub 15 which is rotatably supported in the side walls 10 and 11 of the vat. This cylinder, with its wire mesh surface, is called a "cylinder mold" and it is rotated in the vat by any suitable driving means.

The cylinder mold, moving through the mixture of pulp and water in the vat, picks up, upon its wire mesh surface, a layer of the pulp and carries this material upwardly to a moving belt 16 which is of a width substantially equal to the axial length of the cylinder. The moving belt 16 is ordinarily made of felt and its surface bearing against the surface of the cylinder mold picks up therefrom the layer of pulp and carries it along to the succeeding portions of the paper-making machine. The cylinder molds are of substantial size, being frequently on the order of 10 feet in axial length, and ordinarily there are several of these cylinder molds over which the felt 16 travels, the felt picking up from each mold a layer of the pulp.

Great difficulty and also substantial losses are occasioned if the wire mesh 13 of the cylinder mold is not kept clean. If a portion of the surface of the cylinder mold becomes clogged up with pulp or foreign material, that portion will not function properly in picking up the pulp thereafter, and streaks result in the paper which frequently necessitate scrapping of large portions thereof. The surfaces of these large cylinders are difficult of access and, with ordinary methods of cleaning, it is necessary to shut down the machine, with consequent loss of production, in order to remove an accumulation of material caught in the wire mesh. It is one of the dominant aims of this invention to provide a device which overcomes these difficulties in a thoroughly practical and efficient manner.

Referring again to the drawing, there is shown a housing extending between the two side walls 10 and 11 of the vat and secured thereto, and comprising two longitudinal portions 17 and 18, the housing portion 17 being

shown as slightly greater in diameter than the housing portion 18. As shown in Figure 3, the two housings are preferably integral with each other, being joined by a restricted portion 19.

5 Extending through the housing portion 17 is a shaft 20 provided upon its surface with a screw thread 21 which is preferably of large pitch as shown. In threaded engagement 10 with the thread 21 is a movable member 22 having a part 23 which is slidably received in the restricted housing portion or slot which joins the two housing portions 17 and 18. The member 22 is thus held against rotation by 15 the part 23 thereof, and rotation of the shaft 20 thus moves the threaded member 22 lengthwise of the shaft, the member being moved a distance equal to the pitch of the screw thread 21 at each rotation of the shaft.

20 Within the housing portion 18 is a member 24 which is secured to the member 22 to move therewith, for example by means of a projection 25 on the member 24 threaded into the part 23 of the member 22. The member 25 24 has therethrough a fluid passage, one mouth of which is at the side of the member 24 and into which mouth is threaded a pipe 25. The other mouth of the passage through the member 24 opens at the bottom thereof 30 and threaded thereinto is a pipe 26 which extends through a slot 27 in the housing portion 18. The lower end of the downwardly extending pipe 26 is provided with a bend 28 so that the end thereof is positioned adjacent 35 to, and directed substantially radially at, the surface of the cylinder mold. Upon the end of the pipe 26 is positioned a nozzle 29 for directing against the wire mesh of the cylinder mold a stream of fluid introduced to the 40 nozzle through the pipe 25, the member 24 and the pipe 26.

Connected to the end of the pipe 25 is a flexible hose 30 which leads from an injector 31. The injector 31 is supplied with water 45 through a pipe 32 provided with a valve 33, and with steam through a pipe 34 provided with a valve 35. The injector 31 thus supplies to the flexible pipe or hose 30 hot water or a mixture of steam and water at high pressure, and this water is delivered at high pressure 50 through the pipe 25, the member 24 and the pipe 26, to the nozzle 29. The mouth of the nozzle 29 is in the shape of a slot 29 and the nozzle thus projects a thin fan-shaped stream of water 36 which is of a substantially 55 predetermined width when it strikes the wire mesh 13. This thin blade of water, projected under high pressure against the wire mesh, positively cleans therefrom any accumulations of pulp or foreign material. By rotating the shaft 20 this stream of water is moved across the surface of the rotating cylinder mold in a direction lengthwise of its 60 axis.

65 The shaft 20 is supported at each end by

bearings 37 and 38 positioned in the respective ends of the housing 17. The shaft is also supported intermediate its ends by means of a plurality of spaced bearing members 39 as shown in Figure 3. The bearing member 39 70 comprises a member fixed in the bottom of the housing 17 and having a threaded surface engaging with the threads of the shaft 20. The moving threaded member 22 extends only part way around the shaft 20, being cut away 75 as shown in Figure 3 to clear the bearing member, or bearing members, 39.

Upon the end of the shaft 20 is fixed a gear 40 which meshes with a larger gear 41. The gear 41 is fixed upon a short shaft 42 80 which is rotatably supported in a housing 43 enclosing the two gears. The shaft 42 projects outwardly from the housing 43 and has fixed thereon a crank 44 by means of which the shaft is rotated. By turning the crank 85 44, the shaft 20 is rotated, through the gears 40 and 41, to move the nozzle across the surface of the cylinder mold. As the nozzle is moved in one direction or the other the flexible pipe 30 moves into or out of the housing 90 18. The end of the housing 18 is preferably provided with a curved flange 45 to support and guide the flexible pipe 30 and obviate any sharp corners which might wear the pipe and reduce its life.

A single rotation of the crank 44 will give the nozzle 29 a movement of a predetermined length. The parts are preferably so proportioned that one turn of the crank 44 moves the nozzle a distance substantially equal to 100 the width of the stream 36. For example, let it be assumed that the width of the stream 36 as it strikes the cylinder mold screen is four inches, and that the pitch of the screw is one inch. One rotation of the shaft 20 will then move the four inch stream a distance of one inch. By proportioning the gears 40 and 41 in the ratio of four to one, one rotation of the crank 44 causes four rotations of the shaft 20 and hence a movement of the four inch stream through a distance of four inches. This is of great importance from a practical viewpoint. Each of the cylinder molds of a machine or of several machines is provided with the equipment shown herein. A single operator is able to thoroughly clean all of the cylinder molds throughout the extent of their surfaces, and without missing any portion thereof, quickly and without loss of time. The operator simply moves from one cylinder 110 mold to the other in rotation, giving each of the cranks 44 one turn. During the interval between his visits to any one mold that mold has completed a rotation and the stream from the nozzle has cleaned a circumferential strip equal to the width of the stream. Another turn of the crank moves the nozzle to clean the adjoining four inch circumferential strip. 115

120 From the foregoing it will be seen that there is here provided a device which is of real 130

practical value. The cylinder molds may be cleaned quickly and efficiently without interrupting the operation of the machine and while paper is being made on the machine.

- 5 The cleaning action is positive and entirely efficient. Moreover, an unskilled operator is enabled to clean every portion of the mold with a minimum of effort and time. If it is desired to clean only a small area of the cylinder mold surface, the nozzle may be quickly moved into position to operate upon and clean that portion while the machine continues uninterrupted to make paper. As soon as streaks begin to appear in the paper, due to 10 clogging of a cylinder mold, the condition is easily remedied at once. The cleaning operation does not wear nor in any way harm the wire mesh of the cylinder molds.

This apparatus makes possible the production of a uniformly better grade of paper and very materially lessens the cost of paper manufacture by cutting down waste and preventing shut-downs.

In paper-making machines such as that illustrated herein, the distance between the belt 16 and the top of the vat 10 varies and is ordinarily not more than a few inches. The construction described herein is particularly well adapted to meet this condition. The device is small and compact and is easily modified to meet the various conditions met with in the different paper making machines with which the apparatus is adapted for use. The arrangement of the two housings 17 and 18 in a horizontal plane maintains the vertical dimension of the device at a minimum, and enables it to be fitted into position between the belt 16 and the top of the sides of the vat.

The injector 31 places at the disposal of the operator a wide range of temperatures available at the nozzle 29. By adjusting the valves 33 and 35, the operator may obtain a stream 36 of any desired temperature, ranging from cold water to raw steam under pressure. The nature of the stream which is required varies under different conditions of the cylinder mold surface. It is found that frequently a high temperature is required, which, together with the force with which the stream is directed against the cylinder mold, softens the matted pulp and quickly carries it away. The manual operation of the device is very important, from a practical standpoint, for, as has been pointed out above, the cylinder mold does not require that the cleaning device be operated continually, and, when a portion of the surface does become clogged with pulp or other material, it is of the utmost importance that the cleaning stream be capable of being quickly manipulated into position to clean that portion. In this manner, very substantial losses due to wasted paper and interruptions in the operation of the machine are avoided.

65 As many possible embodiments may be

made of the above invention and as many changes might be made in the embodiment above set forth, it is to be understood that all matter hereinbefore set forth or shown in the accompanying drawing is to be interpreted as 70 illustrative and not in a limiting sense.

I claim:

1. In paper-making machinery, in combination, means adapted to support a layer of pulp upon its surface, means adapted to drive 75 said pulp-supporting means, a nozzle shaped to discharge a flat jet against the surface of said pulp-supporting means to cleanse portions of its surface which have become fouled, sources of supply of steam and hot water, 80 means communicating with said nozzle and leading from each of said sources of supply to provide a jet for said nozzle, and means adapted to move said jet edgewise to direct the same against any desired portion of the surface 85 of said pulp-supporting means.

2. In paper-making machinery, in combination, means adapted to support a layer of pulp upon its surface, means adapted to drive 90 said pulp-supporting means, a nozzle mounted to discharge a jet against the surface of said pulp-supporting means to cleanse portions of its surface which have become fouled, a source of supply of steam and of hot water, an injector connected to each of said sources 95 of supply, a conduit leading from said injector to said nozzle, and means adapted to move said jet to direct the same against any desired portion of the surface of said pulp-supporting means.

3. In paper-making machinery, in combination, means adapted to support a layer of pulp upon its surface, means adapted to drive 105 said pulp-supporting means, a nozzle mounted to discharge a jet against the surface of 100 said pulp-supporting means to cleanse portions of said surface which have become fouled, means adapted to supply said nozzle with a mixture of steam and hot water under high pressure, means adapted to adjust the 110 temperature and the pressure of said water, and manually controlled means adapted to move said jet across said surface transverse to its direction of travel to discharge said jet against any desired portion thereof.

4. In paper-making machinery, in combination, means adapted to support a layer of pulp upon its surface, means adapted to drive 120 said pulp-supporting means, a nozzle shaped to discharge a flat jet against the surface of said pulp-supporting means to cleanse portions of its surface which have become fouled, a source of supply of a mixture of steam and hot water under pressure, means leading from 125 said source of supply to said nozzle, means adapted to move said nozzle transversely of said surface, a reversible manually-operated member, and speed multiplying power transmitting mechanism interposed between said 130

manually-operated member and said nozzle-moving means.

5. In paper-making machinery, in combination, means adapted to support a layer of pulp upon its surface, means adapted to drive said pulp-supporting means, a nozzle shaped to discharge a jet against the surface of said pulp-supporting means to cleanse portions thereof which have become fouled, a source 10 of supply of a mixture of steam and hot water under pressure, means leading from said source of supply to said nozzle, a threaded shaft, a member threaded upon said shaft and having mounted thereon said nozzle whereby said nozzle is moved transversely 15 of said surface in accordance with the speed and direction of rotation of said shaft, a reversible manually-operated member, and speed multiplying gearing interposed between said manually-operated member and said shaft.

6. In paper-making machinery, in combination, means adapted to support a layer of pulp upon its surface, means adapted to drive said pulp-supporting means, a nozzle shaped to discharge a jet against the surface of said pulp-supporting means to cleanse portions thereof which have become fouled, a source of supply of hot vapor under pressure, means 20 leading from said source of supply to said nozzle, a threaded shaft, a member threaded upon said shaft and having mounted thereon said nozzle whereby said nozzle is moved transversely of said surface in accordance 25 with the speed and direction of rotation of said shaft, a reversible manually-operated member, and speed multiplying gearing interposed between said manually-operated member and said shaft, the thread of said 30 shaft being formed in one direction only and the member threaded thereon extending about the shaft.

7. In paper-making machinery, in combination, means adapted to support a layer of 45 pulp upon its surface, means adapted to drive said pulp-supporting means, a nozzle adapted to discharge a jet against the surface of said pulp-supporting means to cleanse portions which have become fouled, a fitting 50 through which fluid passes to said nozzle, a threaded shaft extending transversely of said pulp-supporting means and provided with a member threaded thereon and connected with said nozzle whereby said nozzle is moved 55 parallel to said shaft as said shaft is rotated, a housing portion about said shaft and a relatively offset housing portion about said fitting and within which said fitting travels, and means adapted to prevent the drainage 60 of drip water from the bottom of said second housing portion to said first housing portion.

8. In paper-making machinery, in combination, means adapted to support a layer of pulp upon its surface, means adapted to drive 65 said pulp-supporting means, a nozzle shaped

to discharge a jet against the surface of said pulp-supporting means to cleanse portions of its surface which have become fouled, a threaded shaft extending transversely to the direction of movement of said surface, a member 70 threaded upon said shaft, a fitting connected with said member through which fluid passes to said nozzle, and laterally offset housing portions within which said fitting and said shaft are mounted.

9. In paper-making machinery, in combination, means adapted to support a layer of pulp upon its surface, means adapted to drive said pulp-supporting means, a nozzle shaped to discharge a flat jet against the surface of said pulp-supporting means to cleanse portions of its surface which have become fouled, means adapted to move said jet edgewise across said surface in a direction transverse to that of the movement of said surface, and manually-controlled means adapted upon a single operation to move said jet throughout a distance equal to its width.

10. In paper-making machinery, in combination, means adapted to support a layer of pulp upon its surface, means adapted to drive said pulp-supporting means, a nozzle shaped to discharge a flat jet against the surface of said pulp-supporting means to cleanse portions of its surface which have become fouled, a threaded shaft having a pitch equal to a fraction of the width of said jet, means threaded upon said shaft and connected with said nozzle to move said jet edgewise as said shaft is rotated, a manually-operated rotatable member, and speed multiplying gearing interposed between said member and said threaded shaft proportioned to rotate said shaft with each rotation of said manual member the number of times expressed by the ratio of the width of said jet to the pitch of said thread.

11. In paper-making machinery, in combination, a rotating cylinder mold, a horizontally traveling member adapted to take pulp from said mold, and cleansing mechanism acting upon the surface of said cylinder mold and interposed between the same and the lower surface of said member and comprising a nozzle directed toward the surface of the mold, means adapted to supply said nozzle with a mixture of steam and hot water under pressure, and manually-controlled means adapted to move said nozzle at will in either direction across the surface of said cylinder mold.

In testimony whereof, I have signed my name to this specification this 2nd day of September, 1927.

GILBERT J. SCOFIELD.
